UNITED STATES PATENT OFFICE.

JAMES T. COWLEY, OF LOWELL, MASSACHUSETTS, ASSIGNOR TO THE LAMSON CONSOLIDATED STORE SERVICE COMPANY, OF NEWARK, NEW JERSEY.

CONVEYING APPARATUS.

SPECIFICATION forming part of Letters Patent No. 608,576, dated August 9, 1898.

Application filed April 25, 1895. Serial No. 547,067. (No model.)

To all whom it may concern:

Be it known that I, JAMES T. COWLEY, of Lowell, county of Middlesex, and State of Massachusetts, have invented new and useful 5 Improvements in Conveying Apparatus, of which the following is a specification; and I hereby declare that the following is a full, clear, and exact description of the invention, which will enable others skilled in the art to 10 which it appertains to make and use the same.

My invention relates to new and useful improvements in conveying apparatus; and it has for its object the propulsion of carriers between distant points by means of a propelling-cable, to which the carrier is engaged and disengaged.

My invention consists of certain novel features, arrangements, and combinations hereinafter described, and particularly pointed 20 out in the claims.

In the drawings which accompany this application and illustrate a construction embodying my invention, Figure 1 is a sectional view taken at a point along the line near one 25 of the supporting-brackets and showing a carrier passing said bracket. Fig. 2 is a side view of the same. Fig. 3 is a plan view of the carrier. Fig. 4 is a side elevation of a carrier at a station or terminal along the line. 30 Fig. 5 is a detail side view of one of the brackets used where the carrier passes around a corner. Fig. 6 is a detail view of the cable-gripping mechanism.

Like letters of reference refer to like parts 35 throughout the several views.

Upon the tracks A a carrier B, having wheels C, mounted on journals C' in standards B', is adapted to travel. From the frame of the carrier there extends upwardly an arm B², 40 having at its upper end two flaring fingers B³, each having on its inner side a corrugated surface B⁴, to which the cable X is adapted to wedge in the propulsion of the carrier. These upper fingers B³ are provided with an 45 adjustable screw B⁵ and binding-screw B⁶, the adjustable screw being used to adjust the width of the slot between the fingers B³, so that the cable X will wedge thereon, and the screw B⁶ is to firmly clamp the fingers in their 50 adjusted position.

At different points along the line suitable brackets D are provided, which are supported by hangers D' from the ceiling-plate D³, and said hangers are braced by suitable cross-braces D².

55

E are suitable guide-rods extending the whole length of the line, mounted in the inwardly-extending arms D⁴ on the bracket D.

Pivoted to the lower end of the bracket D is an upwardly-extending cable-supporting 60 lever F, provided at its lower end with a spring F², which tends to keep this supporting-lever in the position shown in dotted lines, Fig. 1, and in full lines in Fig. 5. The upper part of this cable-supporting lever is formed with 65 a concaved surface F³, which is adapted to receive and support the propelling-cable. Near the center of this cable-supporting lever there is provided two lugs F⁵, between which a friction-roll F⁴ is journaled.

70

G represents a pulley journaled upon the pin G', fixed in the bracket D, and its object is to guide the cable while passing around corners.

Supported on the ends of the journal C' of 75 the carrier and in the center from the lug C² is a cam-shaped plate B⁹. This plate is adapted to engage with the friction-roll F⁴ on the cable-supporting lever attached to the bracket D, Figs. 1 and 5, and move the same out of 80 the path of the carrier traveling along the way and passing by one of the brackets.

Journaled on the stud B⁸ and fastened to the upwardly-extending arm B² is a roll B⁷. This roll is adapted to engage with the guide-rods E, extending along the way, and to steady 85 the carrier and keep the same in an upright position and also to guide the carrier while passing by the brackets D and around corners.

Referring now to Fig. 4, which shows a 90 portion of the line where it is desired to steady the carriers to load or unload the same, to the under part of the track A is secured a flat spring H, with upwardly-extending ears H², and secured to the track A by the screw H'. 95 The opposite end of this flat spring is provided with ears H³, which embrace the sides of the track A and guide this end of the spring. As the carrier approaches this portion of the track where the spring is applied thereto the 100

propelling-cable is passed under suitable pulleys J, supported in brackets J'. These pulleys are placed above the track a sufficient height to allow the grip-fingers B³ to pass under the pulley, and by the cable being held in contact with these pulleys J as the carrier approaches this portion of the line the cable will be pulled out from the gripping-jaws B³ on the carrier, and the carrier will travel by momentum onward until it reaches the spring H, when it will wedge thereon and stop the carrier, and when it is again desired to forward the carrier along the line it is simply forced over this spring and forwarded along the line, when the fingers of the gripping-jaws B³ will again engage with the cable and the cable will then continue the carrier along the way.

Having thus ascertained the nature of my invention and set forth a construction embodying the same, what I claim as new, and desire to secure by Letters Patent of the United States, is—

1. In a conveying apparatus, a track, a propelling-cable, a carrier adapted to travel on said track, a gripping mechanism attached to said carrier for engaging with said cable, guide-rods supported above said track for directing said carrier, a lever pivoted at an end and having its free end extending above said track to engage with said cable to support the latter in its proper position relative to the path traveled by said gripping mechanism, a spring normally holding said lever in engagement with the cable, a friction-roller carried by said lever, and a cam-plate mounted on said carrier for engaging with said friction-roller to move said lever out of engagement with the cable.

2. In a conveying apparatus, a track, a propelling-cable, a carrier adapted to travel on

40 said track, a gripping mechanism attached to said carrier for engaging with said cable, guide-rods supported above said track for directing said carrier, a lever pivoted at an end and having its free end extending above said track to engage with said cable and to support the latter in its proper position relative to the path traveled by said gripping mechanism, a spring normally holding said lever in engagement with the cable, and a cam-plate mounted on said carrier for engaging 45 said lever to move the latter out of engagement with the cable.

3. In a conveying apparatus, a track, a propelling-cable, a carrier adapted to travel on said track, a gripping mechanism attached to said carrier for engaging with said cable, guide-rods supported above said track for directing said carrier, a lever pivoted at an end and having its free end extending above said track to engage with said cable to support 50 the latter in its proper position relative to the path traveled by said gripping mechanism, a spring normally holding said lever in engagement with the cable, a friction-roller carried by said lever, and a cam-plate mounted on 55 said carrier for engaging with said friction-roller to move said lever out of engagement with the cable.

In testimony whereof I have signed my name to this specification, in the presence of two subscribing witnesses, on this 12th day of April, 1895.

JAMES T. COWLEY.
